DYE TUB

Thomas D. McClellan, Passaic, N. J.

Application August 14, 1936, Serial No. 95,984

2 Claims. (Cl. 68—15)

This invention relates to dye tubs for use in textile dyeing plants.

The objects of the invention are:—to provide an improved container for the dye bath; to provide an improved means for supplying water to the bath; to provide means for controlling the temperature throughout the bath; to provide means for controlling the addition of dyestuff and chemicals and for distributing the same throughout the bath; to provide for circulation of the bath so as to obtain a uniformly dyed product and to prevent damage to the material in the dyeing operation; to prevent loss of heat and loss of vapor from the bath; to provide a tub which can efficiently accommodate batches of different sizes; to prevent loss due to tangling of the material or unevenly dyed portions; to reduce the quantity of dye bath required for a given batch of material; and, in general, to improve the efficiency of operation of the dye tub.

One feature of the invention consists in the provision of a tub which is so shaped as to reduce the quantity of liquid required for dyeing the material. For this purpose, the bottom of the tub is caused to conform, in general, to the space occupied by the material in its passage through the dye bath. In one embodiment, the tub is provided with a bottom which forms a chamber adapted to receive the material as it is laid therein in folds or pleats and which slopes upwardly along the general path taken by the material as it is withdrawn from the tub so that the normally unused portions of the bath, with which the material does not come in contact, are eliminated.

A further feature consists in the provision of means for continuously removing portions of the dye bath and re-circulating the same, preferably in the general direction of travel of the material. Heating means is provided for the re-circulated liquid whereby the liquid is heated after being removed from the bath and before being reintroduced therein. In this manner, the temperature of the liquid in the various parts of the bath is maintained substantially constant.

In one embodiment, the heat is supplied by steam coils over which the re-circulated liquid passes and which supply heat to the liquid without introducing steam directly into the bath or otherwise contaminating the same. Means is also provided for introducing water, dyestuff and chemicals to the re-circulated liquid before it is reintroduced into the dye bath and at a rate such that the added material is dispersed in a large

volume of the dye liquid before the same comes in contact with the material.

In order to prevent a loss of heat and escape of vapor, a hood is provided over the entire tub, having windows through which the progress of the dyeing operation can be observed. These windows are mounted in doors having means for elevating the same to afford access to the tub when desired.

A further feature consists in the provision of hydraulic means to elevate the doors and means to effect a tight seal with the doors when the same are closed, whereby the fumes and mist are prevented from escaping into the atmosphere of the dye house.

A further feature consists in the provision of a conveyor carrying samples of the material which may be removed for inspection, thereby avoiding the necessity for cutting portions from the main material or stopping the movement of the material for this purpose.

A further feature consists in the provision of adjustable means for guiding materials of different weights onto the reel.

Various other features and advantages will be apparent as the nature of the invention is more fully disclosed. The invention itself, however, may be better understood by referring to the following description, taken in connection with the accompanying drawings, in which one embodiment thereof has been set forth for purposes of illustration.

In the drawings,

Figure 1 is a side elevation of a dye tub constructed in accordance with this invention; 35

Figure 2 is an end elevation thereof showing the door in elevated position;

Figure 3 is a section taken on the line 3—3 of Figure 2, showing the seal for the door;

Figure 4 is a horizontal section taken along the line 4—4 of Figure 1;

Figure 5 is a vertical section taken along the line 5—5 of Figure 4;

Figure 6 is a horizontal section taken along the line 6—6 of Figure 5; and 45

Figure 7 is a vertical transverse section taken on the line 7—7 of Figure 6.

Although certain specific terms are used herein for convenience in referring to various details of the invention, it is to be understood that these terms are to be given as broad an interpretation as the state of the art will permit.

Referring to the drawings more in detail, and more particularly to Figure 5, the invention is shown as comprising, in general, a tub 10 having 55

a bottom 11 forming a chamber 12 having a curved section as shown in Figure 5 and adapted to receive the material 13 which is laid therein in folds or pleats 14, as by an oval reel 15, and 5 having an upwardly sloping section 16, conforming generally to the path taken by the material as it is withdrawn from the chamber 12 by a second reel 17. The sloping section 16 terminates at a heating chamber 18, containing a 10 steam coil 19, into which the bath discharges in its passage through the tub. The bath, after being heated by the coil 19, passes through a pipe 20 and is thence re-circulated, in the manner to be later described, through a flow box 21 which 15 is disposed above the bath at a point beneath the reel 18, so that the liquid is caused to flow in the direction of travel of the material from the flow box 21, through the bath, to the heating chamber 18. A hood 22 encloses the entire bath 20 and the reels so as to conserve heat and to prevent escape of liquid or vapors. This hood is provided with windows 23 for the purpose set forth.

The details of construction will be better understood by referring to Figures 1 and 2. In these figures, the tub 10 and hood 22 are shown as supported by a framework comprising a plurality of uprights 25 by which the assembly is supported and joined by horizontal members 30, which support the tub 10, and by horizontal members 27 and 28 which strengthen the assembly and provide supports for the hood 22. The tub 10 is provided with a bottom 11, above described, and with side members 30 which are 25 supported by the horizontal members 26. The pipe 28 leading from the heating chamber 18 communicates with a pump section 32 (Figure 1) having an impeller (not shown) therein, driven by a motor 33 which may be mounted above the level of the bath on the outside of the tub (Figures 1, 3 and 4) and is connected to the impeller by a coupling mechanism 34. The impeller is adapted to lift the liquid from the pipe 28 through a riser 35 and to discharge the same through a pipe 36 (Figure 4) into the flow box 21 (Figures 5, 6 and 7). The impeller is preferably designed to lift the liquid without agitation and without introducing air therein so as to prevent deterioration of the bath. A standard type of impeller, capable of lifting the liquid without applying centrifugal force may be used.

The flow box 21 (Figure 5) is in the form of an open-top box extending across the bath and is provided with a front plate 40, the bottom of which is shaped to form a slot 41, extending across the tub, through which the liquid discharges to a lip 42 formed on the flow box 21 and terminating at the level of the bath. The lip 42 is rounded upwardly to prevent injury to any material that may come in contact therewith. The slot 41 is shaped in accordance with the pressure distribution across the flow box 21 so that a uniform distribution of liquid across the bath is obtained. It will be noted that the head of liquid in the flow box, caused by discharge from the pipe 36, is greatest at a point some distance from the end of the discharge pipe and decreases in both directions from that point. The slot 41 accordingly is made narrowest at the point of greatest head or pressure and increases in width in inverse ratio to the change in pressure, being widest at the two ends of the flow box where the pressure is lowest. The shape of the slot 41 may be computed mathematically or may be determined by measuring 70 the head of liquid at the various points in the flow

box and should be such as to provide a uniform discharge across the entire bath.

Water is supplied when required to the bath by a suitable pipe 43 (Figures 5 and 6) which may terminate above the heating chamber 18. Water 5 may also be introduced into the bottom of the tub by pipes 44 which also serve as a drain when the tub is to be emptied. The pipes 44 are provided with valves 45 and communicate with a water supply pipe 46 controlled by a valve 47 and with 10 a drain pipe 48 having a valve 49. By suitable actuation of the various valves, wash water can be admitted to the tub through the pipes 44 or the contents of the tub can be drained through the drain pipe 48.

The dyestuffs and chemicals are supplied from a receiver 50, located at the side of the tub, and having a screen 51. A plurality of pipes 52 and 53 (Figure 1) of different capacities and having valves 54 and 55, respectively, are connected to 20 feed the solution from the receiver 50 to the re-circulation pipe 20. The valve 54 may be used for controlling the admission of dye liquid from this receiver, and the valve 55 may be used to introduce other chemicals which may be supplied 25 to the pipe 20 at a more rapid rate. Other pipes of different sizes may be used or other means, such as differently sized orifices, may be used to control the flow of liquid as desired, so that the rate of addition becomes a constant and is not 30 dependent upon a variable valve adjustment. Obviously, water may also be introduced from the receiver 50, if desired.

The pipes 52 and 53 may be connected to a discharge line 56, having a draw-off valve 57 which provides means to draw water from the bath to be used for mixing chemicals and dyes so that the total quantity of bath may be kept constant. A discharge pipe 58, having a control valve 59, may be connected to the riser 35 to introduce re-circulated liquid into the receiver 50 for use in flushing out the receiver, for assisting in distributing the added dyestuff throughout the bath, or to provide liquid for mixing the dyestuff or chemicals. This pipe 58 terminates short of the screen 51 so as to permit removal of 40 said screen.

A discharge pipe 60, having a control valve 61, may be connected to the pipe 28 to provide means for carrying away the wash water when washing upwardly from the pipes 44. Scum may be removed from the heating chamber 18 by an overflow launder 62 (Figure 5) connected by a pipe 63 to the discharge pipe 60.

The reels 15 and 17 are supported by suitable bearings (not shown) from the horizontal members 27 of the framework. The reel 15 is preferably oval so as to lay the material in the tub in folds or pleats in the usual manner. The reel 17 is preferably circular for withdrawing the material from the tub at uniform rate. The speed of operation of the reels may be varied as required. The periphery of the reels may be provided with spaced rods 64 of molded phenol condensation product, such as Micarta, and a covering 65 of similar material in the form of a flat sheet may be applied over the rods 64 or attached directly to the reel supports. I have found that this material has the property of gripping the material for pulling the same without injury. 70 The material may adhere somewhat to the Micarta surface, in which case the folds are laid somewhat longer than the normal throw of the reel.

Suitable guide plates 66 and 67 are slidably 75

mounted on channels 68 carried by the frame for guiding the material from the bath onto the reels. The plate 66 is positioned to guide material onto the reel 17 when this reel is being used 5 to withdraw material from the bath. This plate has three sets of holes 69 which are of different sizes and are differently spaced for guiding materials of different weights. The proper set of holes may be brought into position for guiding 10 the material by sliding the plate 66 in the channel 68.

The plates 67 are provided for guiding the material onto the reel 15 when the material is withdrawn from the bath directly onto this reel.

15 These plates are also slideable and are provided with rows of holes 70 which are similar to the holes 69 in the plate 66. Two separate plates 67 are used because the space is not sufficient to permit sliding adjustment of one large plate.

20 The hood 22 comprises sides 71, ends 72 and a top 73, all of which are suitably supported by the framework. The windows 23 are mounted in doors 74 which slide in channels 75 located at the ends 72 of the tub and are operated by suitable 25 hydraulic lifts, such as cylinders 76, mounted above the doors 74, and having pistons (not shown) connected to rods 77 which are attached at the lower part of the doors 74. Fluid is supplied to the cylinders 76 by a pipe 78 controlled 30 by a two-way valve 79 connecting the pipe 78 to a supply pipe 80 or a discharge pipe 81.

The doors are sealed hydraulically by a hose 82 held in a channel 83 which surrounds the door opening and bears against the door around its 35 entire periphery when distended by fluid pressure, making possible the treatment of material at temperatures above the boiling point and the retention of valuable vapors in certain processes. The hose 82 is connected to a suitable source of 40 fluid pressure (not shown), such as a water main or a compressed air line. When the seal is to be effected, the fluid is supplied to the hose 82 until it is expanded or distended to make a tight contact around the entire door. When the pressure 45 within the hose 82 is released, the door can be moved freely. Obviously, other types of seal may be used, particularly if a tight seal is not essential.

A take-off reel 84 of any desired type, such as 50 a vacuum reel, may be positioned at one end of the tub and supported by an arm 85 attached to one of the uprights 25. This reel may be used for removing the batch of material from the tub and at the same time extracting excess water 55 therefrom. One or more longitudinal partitions (not shown) may be provided in the tub so as to divide the same into two or more compartments, which may be used separately or together depending upon the size of the batch being treated. 60 Side bars 86 (Figure 6) are provided to keep the material out of contact with the sides of the tub.

A conveyor belt or chain 87, carrying samples of the material, is mounted above the heating chamber 18 and is driven by a belt 88 from the 65 reel 17. This belt 87 dips in the bath and receives treatment similar to that of the material on the reels 15 and 17. The door 74 is provided with a port 89 through which the belt 87 may be viewed and which may be opened to permit removal of samples for observation or test.

In the operation of this device, the dye solution is prepared at the proper concentration and temperature according to the requirements and is circulated through the bath while the material 75 is being passed therethrough from the reel 15

to the reel 17 in the manner above described. As the dyeing operation proceeds, the temperature may be carefully regulated by suitable adjustment of the rate of flow of the liquid through the re-circulation pipe 20 and of the heat supply to 5 the steam coil 19. The temperature and rate of circulation can be independently controlled by varying the above-mentioned adjustments. At the same time, the dye can be built up as required by mixing the dye solution in the receiver 50 and 10 introducing the same into the pipe 20 by suitable actuation of the valves 54 and 55. In this way, the dye is thoroughly dispersed in a large volume of solution before it is introduced into the tub, so that the dye cannot contact the material in a 15 concentrated form. The rate of addition of the dye can be adjusted with respect to the rate of circulation of the liquid and the number of revolutions of the reel so that a suitable distribution is obtained. Furthermore, the flow box 21 holds 20 a substantial quantity of liquid and provides a further opportunity for the dye to be thoroughly dispersed in the liquid before it is supplied to the bath.

The flow of liquid through the tub assists in 25 the removal of impurities, such as lint, lime soaps, etc. into the heating chamber, where they are removed by the launder.

Since the tub is shaped to conform to the path of the material, the amount of excess dye bath 30 is reduced to a minimum. The cost for dyestuffs and chemicals and the cost of heating the same are correspondingly reduced. Furthermore, the maintenance of a uniform temperature throughout the bath eliminates local variations in temperature which occur when the bath is heated without forced circulation. This permits an accurate control of the dyeing conditions and reduces the possibility of injuring the material or 35 dyestuffs by improper temperatures. 40

By suitable adjustment of the operating characteristics, the dye may be added at a rate determined by the speed of travel of the material through the tub. In this way, an accurate control of the color and condition of the material 45 may be obtained.

The washing of the material is facilitated because the water may be introduced by the pipes 44 and caused to flow with the material, thence into the heating chamber 18, whence it is removed through the pipe 60 or it may be introduced into the tub by the pipe 43 and caused to flow in a reverse direction and out through the pipes 44 and 48 for flushing out the tub and washing the material. By providing the various 50 controls, including the receiver 50, on the outside of the machine, the dyestuffs or chemicals 55 may be mixed and introduced when the tub is operating without opening the hood or otherwise interfering with the continuous operation of the 60 dyeing process.

During the run, samples may be taken from the belt 87 without stopping the machine. When it is desired to raise the doors 74, the hose 82 is first collapsed by releasing the fluid therein and 65 the valve 79 is actuated to supply fluid pressure to the cylinders 76. The bath is then accessible for adjustment or for inserting or removing the material. When the doors are closed and sealed, escape of vapor or fumes is prevented and the 70 atmosphere of the dye house is kept free from mist.

I have found that some dyeing operations are a function of the speed of the material. By closing the doors 74, I am able to run the material 75

at a high speed, if necessary, without throwing liquid from the tub. This is of particular importance with some kinds of material.

By washing the material in the normal direction of flow, the impurities are removed to the launder and are prevented from contaminating the material and necessitating subsequent cleaning. The scum is removed continuously by the launder 62 and pipe 63. A screen may be mounted above the heating coil 19, if desired, to prevent impurities from being re-circulated.

It is to be understood that the heating chamber may be at a higher level than the flow box to obtain gravity flow of liquid, in which case a pump may be used to raise the liquid from the bath to the heating chamber. In some instances, the direction of flow of dye liquid may be reversed in the bath.

It is to be understood that various combinations of adjustments may be made according to the particular material being treated and to the dye solution used so as to obtain any desired result.

While a specific embodiment of the invention has been disclosed for purposes of illustration, it is obvious that the invention is not to be limited thereto but that various changes and modifications may be made therein as will appear to a person skilled in the art. The scope of the invention is only to be limited in accordance with the following claims when interpreted in view of the prior art.

I claim:

1. In a tub containing a dye bath, means to introduce material in a folded or pleated pile, means to withdraw the material from the bottom of said pile in an upwardly inclined path, said tub having a bottom forming a chamber to receive the pile of material and extending therefrom in an upwardly inclined direction conforming generally to the path of withdrawal of the material, means to withdraw portions of the bath from said tub, means to heat the portion thus withdrawn, a flow box, and means to introduce the withdrawn portion of the bath into said flow box, said flow box having a slot through which the dye liquid flows into said tub, said slot varying in size across the tub in accordance with the pressure distribution in said flow box so as to maintain a uniform rate of discharge across the entire tub.

2. In a dye tub, means to continuously introduce a dye liquid comprising a flow box extending across the tub, a pipe to introduce the dye liquid into said flow box and a slot in said flow box through which the dye liquid flows into said tub, said slot varying in size across the tub in accordance with the pressure distribution in said flow box so as to maintain a uniform rate of discharge across the entire tub.

THOMAS D. McCLELLAN. 30
